UNITED STATES PATENT OFFICE.

HUGH KENNEDY AND JOHN W. HIGGS, OF SHARPSBURG, ASSIGNEES TO THE
PITTSBURG MINERAL WOOL COMPANY, OF ETNA, PENNSYLVANIA.

APPARATUS FOR MANUFACTURING MINERAL WOOL.

SPECIFICATION forming part of Letters Patent No. 328,227, dated October 13, 1885.

Application filed June 1, 1885. Serial No. 167,355. (No model.)

To all whom it may concern:

Be it known that we, HUGH KENNEDY and JOHN W. HIGGS, of Sharpsburg, in the county of Allegheny and State of Pennsylvania, have 5 invented a new and useful Improvement in Apparatus for Manufacturing Mineral Wool; and we do hereby declare the following to be a full, clear, and exact description thereof, reference being had to the accompanying drawings, in which—

Figure 1 is a perspective view of one form of our improved device. Fig. 2 is a plan view. Fig. 3 is a section on the line *w w* of Fig. 2. Figs. 4 and 5 are respectively plan and side views illustrating the operation. Figs. 6, 7, 8, and 9 are views of modifications, Fig. 7 being a section on *x x* of Fig. 8, 8 a section on *y* of Fig. 7, and 9 a section on *z z* of Fig. 8. Figs. 10 and 11 are respectively a longitudinal 20 section and a perspective view of another modification.

Like letters of reference indicate like parts.

Our invention consists in apparatus for converting a stream of molten slag into fiber or mineral wool by treating it with a jet or jets of steam or air which surround it on all sides, 25 preferably giving the projected stream of wool a swirling or twisting motion.

Referring to Fig. 1, *a* indicates a steam-pipe 30 having a series of five jet-pipes provided with flattened discharge ends or orifices. The central jet-pipe, 1, has its flattened orifice extending in a horizontal direction. On either side, and at or about the same level, is a jet-pipe, 35 2, the flattened orifice of which extends in a vertical direction, and above the jet-pipe 2 are two other jet-pipes, 3, the flattened orifices of which extend in a horizontal direction, but are not on the same level, so that the stream or 40 jets therefrom shall tend to pass each other at the point of meeting. The ends of the jet-pipes 1 and 2 turn upward, and the ends of the pipes 3 turn inward toward each other and extend some distance beyond the ends of the 45 pipes 1 and 2, so that there is formed between the ends of the jet-pipes a space, 4, into which the stream of molten slag from the trough or pipe *b* is caused to fall.

The operation of this device is illustrated in 50 Figs. 4 and 5, where, it will be observed, the

stream of molten slag from the trough *b* falls into the space 4 in front of the end of the central or main jet-pipe, 1, where, being caught by the jet of steam from said pipe, it is projected upward and outward. The tendency of 55 the jet 1 is to spread the stream of slag into a fan shape, and to convert only the central portion into fiber, while the sides would be turned into granules or shot. This is prevented by the jets from the pipes 2; which, meeting the 60 spreading stream of slag projected by the pipe 1, force it inward and keep it within the range of action of the jet from the pipe 1, as well as themselves acting upon it to convert it into fiber. The upward tendency of the stream of 65 slag thus given to it by the pipes 1 and 2 brings it within the range of the jets from the pipes 3, which, as they do not exactly register, give it a swirling or twisting motion and hold it down within the range of action of the jets from 70 the pipes 1 and 2. The jets from the pipes 1, 2, and 3 all converge to a point, 8, some inches away from the ends of the pipes 3, where they practically unite into a single stream, and from that point the stream of molten slag spreads 75 outward into a conical shape and enters the end of the receiving-conduit *c*. During the passage of the slag from the point 4 to the centering-point 8 of the jets it is thoroughly converted into fiber, so that there are so few granules formed that the entire product of the blow 80 is salable as "No. 1" wool.

In Figs. 6, 7, 8, and 9 we show a modified construction, which consists in a hollow casting, *d*, to which the steam is supplied by a pipe, 85 *d'*, and which is provided with a central opening, *d''*, and a series of converging jet openings or slots, 5, 6, and 7, extending through the sides around the central opening, *d''*. When applied for use, the casting *d* is placed in an 90 inclined position, as shown in Figs. 6 and 7, under the slag-trough *b*. A stream of slag then falls through the opening *d''*, where it encounters the jet of steam from the slot 5, which in this instance answers to the jet-pipe 1 of the 95 first construction. The stream projected by the jet 5 is treated on the other three sides by the jets from the slots 6 and 7. The angles of inclination of the slots are different, but they are caused to converge to a point, 8, as in the 100

first construction. By giving a slight lateral slant to either of the other two opposite jets a swirling motion can be given to the slag.

In Figs. 10 and 11 the construction consists 5 of a hollow tubular casting, *c*, provided with a central opening, *e'*, through which the stream of molten slag passes, a steam-pipe, *e*², which supplies steam, and an inclined jet-opening, *e*³, at the other end, which gives to the jet of 10 steam a conical shape.

In all the constructions named the stream of molten slag is enveloped on all sides by jets of steam or air, which cause it to be thoroughly treated and converted into mineral wool. We 15 prefer the construction shown in Figs. 1 to 5, as we have had it in practical use for some time, and it has been proven to be a thorough and efficient means of carrying our invention into practice.

20 We prefer to use the construction of apparatus which gives a swirling motion to the projected stream of slag, for the reason that the thorough treatment of the slag is thereby insured, and the fiber produced will be lighter 25 and better.

We do not desire to claim the method herein described, as that forms the subject-matter of a separate application.

What we claim as our invention, and desire to secure by Letters Patent, is—

1. In the manufacture of mineral wool, a 30 converting device having a central jet-pipe for spraying the slag and side jet-pipes for preventing the lateral spread of the sprayed stream, substantially as and for the purposes 35 described.

2. In the manufacture of mineral wool, a converting device having a central jet-pipe for spraying the slag, side jet-pipes for preventing the lateral spread of the sprayed stream, 40 and other jet-pipes for giving a twisting motion to the same, substantially as and for the purposes described.

In testimony whereof we have hereunto set our hands this 23d day of May, A. D. 1885.

HUGH KENNEDY.

JOHN W. HIGGS.
